[57] CLAIM

The ornamental design for a round lasagna product, as shown and described.

DESCRIPTION

FIG. 1 is a perspective view of the round lasagna product, showing my new design;

FIG. 2 is a top plan view thereof;

FIG. 3 is a side elevational view thereof, the undisclosed side being the same;

FIG. 4 is a bottom plan view thereof; and

FIG. 5 is an enlarged partial sectional view thereof, taken along line 5—5 of FIG. 2;

FIG. 6 is an enlarged perspective view of the lasagna product, positioned within a pan or package, which is shown in broken lines as environmental structure, which does not form a part of the claimed design; and,

FIG. 7 is an enlarged partial sectional view of the lasagna product, as shown in FIG. 6, taken along line 7—7 of FIG. 6.

The broken lines shown in FIGS. 6 and 7 are for illustrative purposes only and form no part of the claimed design.
